G. SPIESS.
DRIVING MECHANISM FOR SHEET FEEDERS.
APPLICATION FILED APR. 2, 1909.

Patented May 4, 1915.

UNITED STATES PATENT OFFICE.

GEORG SPIESS, OF LEIPZIG CONNEWITZ, GERMANY, ASSIGNOR TO ARTHUR SPIESS, OF MANNHEIM, BADEN, GERMANY.

DRIVING MECHANISM FOR SHEET-FEEDERS.

1,138,327.

Specification of Letters Patent.

Patented May 4, 1915.

Application filed April 2, 1909. Serial No. 487,469.

To all whom it may concern:

Be it known that I, GEORG SPIESS, a subject of the Emperor of Germany, residing at Leipzig Connewitz, Germany, have invented 5 new and useful Improvements in Driving Mechanism for Sheet-Feeders, of which the following is a specification.

This invention has reference to improvements in driving mechanism for sheet feeding devices and pertains particularly to that type of sheet feeding apparatus in which a bank of feathered sheets is fed around a transfer roller onto a work table and then transported along said table to a set of friction wheels which transfer the top sheet of the supply.

In devices heretofore employed the actuation of the transfer roll occurs simultaneously with the movement of the means of friction wheels that separate the top sheet. Such apparatus suffers from the disadvantage that the sheets frequently stop and pile up in front of the friction wheels and that the transfer roll will not act evenly if operated by spring power.

It is the purpose of the present invention to cause the transfer or feed of paper by the transfer roll at a time when the friction wheels have been raised and are inactive.

30 The invention is illustrated in the accompanying drawing in which:

Figure 1 represents in side elevation a driving mechanism for sheet feeders embodying in desirable form the present invention. Fig. 2 is a plan view of same and Fig. 3 is a detail view in side elevation showing a friction wheel in the inactive position.

Similar characters of reference denote 40 like parts in all the figures.

In the drawing A represents the transfer roll around which passes the supply or bank of paper B onto the work table C where it is fed forward in the usual manner by transfer tapes or other means until the top sheet reaches the friction wheels D. This feed of paper by the transfer roll A takes place according to the present invention at predetermined intervals when the friction wheels have transferred the top sheet and are raised and therefore inactive. The feeding forward of the bank of paper then brings the next sheet into a position to be transferred and the friction wheels descend to effect the transfer.

In the device illustrated a shaft N rotates continuously. This shaft carries a crank O to which a crank rod P is movably attached. The crank rod P is slotted at the opposite end. A swing arm F is pivotally secured 60 on the frame work with its upper end portion as shown in Fig. 1. On the side near the crank rod P the swing arm carries a pin F¹ which passes through the slot of said crank rod. Somewhat below the pin F¹ a spring Q is attached to the swing arm with one end while the other end is stationarily secured, Figs. 1 and 2. The bottom end portion of the swing arm F below the spring Q connects movably with a horizontal bar 70 G. The other end of the bar G has an adjustable or pin and slot connection with a swing lever H provided on its upper end portion with a pawl I. The shaft of the ratchet wheel K carries a gear wheel L 75 which engages with a gear wheel M mounted on the shaft of the transport roll A. The spring Q connected to the swing arm F has the tendency to draw said swing arm toward the left in Fig. 1 and thereby the 80 horizontal bar G which in turn actuates the swing lever H that carries the pawl I. When the spring Q pulls the arm F and the bar G toward the left the upper end of the swing lever H moves toward the right 85 because it is secured on the shaft of the ratchet and thereby the pawl I is out of engagement with the teeth of the ratchet leaving the transport roll A at rest. When the swing arm F moves toward the right in 90 Fig. 1 during another phase of the operation of the device by means of the slotted crank rod P which is actuated by the continuously rotating shaft N, the bar G moves toward the right while the upper end of the 95 swing lever H moves toward the left and the pawl engages the teeth of the ratchet thereby moving same in the direction of the arrow to a certain distance according to the throw of said lever H. The gear L then 100 actuates the gear M and thereby the transport roll A a corresponding distance in the direction of the arrow as shown in Fig. 1. It is plainly understood from the above 105 that upon the rotation of the shaft N the crank rod P will travel a certain distance without effecting the movement of the swing arm F because it is slotted as above described. For the purpose of transporting the bank of paper and bringing one sheet to 110

the transfer device the crank O has to make one revolution in the direction of the arrow as shown in Fig. 1. During the first half of said revolution the swing arm is not affected 5 by the crank rod and the spring Q draws same toward the left releasing the pawl I. During the second half of the revolution of the crank O or rather at the end of the third quarter of said revolution the swing arm F 10 is moved by the crank rod to the right whereby the pawl I is actuated so as to move the ratchet wheel and thereby the transport roll to a certain extent. As above stated the friction wheels D are down upon the top 15 sheet of the paper during the first half of the revolution of the crank O and transfer said sheet until it reaches further transportation devices. The friction wheels then are raised by suitable means into the position 20 shown in Fig. 3. This raising mechanism is preferably of the type shown in my prior Patent No. 967,077 dated Aug. 9, 1910, it does not form part of this invention and therefore is not shown or described here. The 25 movement of the swing arm F is then temporarily prevented by a suitably supported rack R which is connected to the lower end portion of the swing arm as shown in Fig. 2. The teeth of the rack may be engaged by a 30 stop tooth S when the friction wheels are in a raised position as shown in Fig. 3. Each friction wheel D is supported on a bell crank lever D¹ which is mounted on a shaft E. Connected thereto are the links T and U 35 which latter carries a support V to which a stop tooth S is attached which is normally kept out of engagement with the teeth of the rack by a spring S¹ suitably supported on the frame work. However when a friction 40 wheel D is raised the arms T and U are actuated and the tooth carrying support or arm V forced down so that said stop tooth S engages the rack. At this moment the swing arm F is prevented from further 45 movement. Thus the stop tooth S defines the distance which the roll A travels so that one sheet is transported under the friction wheels D and no farther. The friction wheels D descend sooner or later in accordance 50 with the size of the sheet that is transported whereby the links T, U, and V are actuated so that the spring S¹ may pull up the stop tooth S from the rack. During the second half of one revolution of the 55 crank the friction wheels remain in a raised position and the crank rod forces the swing arm to the right actuating thereby the pawl I which causes the movement of the transport roll A while the stop tooth glides over the 60 teeth of the rack. Thus the pawl I is operated for effecting the movement of the transport roll at a time when the friction wheels are in a raised position and therefore inactive. Accordingly the actuating mechanism

for the roll A is made to depend upon the 65 driving arrangement of the friction wheel axle E. During succeeding revolutions of the crank O the described cycle of operations is repeated.

In the described manner the continuously 70 rotating shaft N with crank O actuates the slotted crank rod P whereby the pin F¹ of the swing arm F is moved horizontally forward and backward. The swing arm F being normally pulled toward the left by the 75 spring Q pulls the rod G to the left and all mechanism movably connected to its other end. The swing lever H secured to the other or right hand end of the rod G with its lower end thus operates the pawl I on its 80 upper end and establishes periodically engagement with the ratchet K. The shaft of the ratchet carrying the gear L is thereby moved and engages the gear M on the shaft of the transport roll A whereby the bank of 85 sheets is moved a certain distance bringing the top sheet under the friction wheels or rolls D which sheet is then transported to further transportation devices. Upon the upward movement of the friction wheels as 90 shown in Fig. 3 the link mechanism T, U, V is actuated whereby the stop tooth S normally held out of engagement with the rack R in connection with the swing arm F is made to descend and enter the teeth of said 95 rack. This engagement of the stop tooth S with the rack R prevents the swing arm F from further movement until the friction 100 wheels or rolls D descend again. This engagement of the stop tooth with the rack 105 occurs when the swing arm F by virtue of the continuous rotation of the shaft N is in the position indicated in Fig. 3 that is to the left and the pawl I accordingly is out of engagement with the ratchet K. The extent of the feeding stroke of the pawl I being equal to the extent of the inactive stroke of this pawl, therefore, is governed by the engagement of the stop tooth S with the rack R. During this time the transport 110 roll does not move but upon further rotation of the shaft N the entire cycle of operations is repeated.

I claim as my invention:

1. Sheet feeding mechanism comprising a 115 roll for feeding a bank of feathered sheets of paper, friction wheels adapted to be raised and lowered out of, and into, feeding positions for transferring the top sheet when in contact therewith, means for actuating the bank feeding roll when the friction 120 wheels are inactive, and means in connection with said friction wheels dependent for inoperativeness upon the length of time the said wheels are in the lowered position, to 125 control the extent of movement of the transport roll.

2. Sheet feeding mechanism comprising a

roll for feeding a bank of feathered sheets, friction wheels adapted to be raised and lowered for transferring the top sheet when in contact therewith, pawl and ratchet mechanism for actuating said roll, a rack bar having an operative connection with said pawl and ratchet mechanism, a stop tooth adapted to be brought into engagement with said rack to limit the movement thereof and control the operation of said pawl and ratchet mechanism, and means connected with said friction wheels for governing the position of said stop tooth.

3. Driving mechanism for sheet feeding devices to transfer sheets of paper at a time when the sheet transporting means are periodically inactive comprising a roll for feeding a bank of feathered sheets of paper, combing wheels, a shaft for said wheels adapted to be raised and lowered with the wheels, and means in connection with the said shaft to transmit the motion of the shaft to the roll, said means being actuated

when the combing wheels are raised to inoperative position. 25

4. Driving mechanism for sheet feeding devices to transfer sheets of paper at a time when the sheets transporting means are periodically inactive comprising a roll for feeding a bank of feathered sheets of paper, combing wheels, a shaft for said wheels adapted to be raised and lowered with the wheels, a rack bar having an operative connection with the roll, a stop tooth adapted to be brought into engagement with the rack to limit its movement, and link mechanism connected with the combing wheels for governing the position of the said stop tooth.

In testimony whereof I have hereunto set my hand in the presence of two subscribing witnesses.

GEORG SPIESS.
